(Cl. D52—2)

FIG. 1

FIG. 2

FIGURE 1 is a front view of the cylindrical liquid dispensing pump showing our new design.

FIGURE 2 is a side perspective view of the cylindrical dispensing pump shown in FIGURE 1.

The rear of the dispensing pump is a mirror image of the front view shown in FIG. 1, and the undisclosed side is substantially the same in appearance as the side shown in FIG. 2.

The essential features of the design are shown in full lines.

We claim:

The ornamental design for a cylindrical liquid dispensing pump as shown and described.
